UNITED STATES PATENT OFFICE

2,502,513

SHOE SHAPING MACHINE

Karl Engel, Swampscott, Mass., assignor to
United Shoe Machinery Corporation, Flemington, N. J., a corporation of New Jersey

Application August 22, 1946, Serial No. 692,168

3 Claims. (Cl. 12—1)

1

This invention relates to machines for shaping shoe uppers and is herein illustrated in its application to machines for shaping the foreparts of shoes having open back parts.

In the manufacture of shoes having open back parts in accordance with the slip lasted method of construction, so called, a prefitted upper is attached to a shoe sole and thereafter a last or form is inserted into the shoe to expand the upper to its final shape. It is an object of the present invention to provide a machine which will shape the uppers of such shoes without the aid of lasts. It is a further object of the invention to provide a machine which will enable an operator to achieve a higher production than is possible under present methods of manufacture while substantially reducing the physical effort required.

With the above objects in view the present invention in one aspect thereof comprises a machine for shaping shoe uppers having a support for an end portion of a shoe bottom herein illustrated as a sole and heel assembly, said support being herein illustrated as a block having the shape of the heel portion of a last and arranged to engage the foot-facing surface of said shoe bottom assembly, an eccentrically mounted presser member or roll for clamping said bottom assembly against said support, means for positively holding said presser member against bodily movement longitudinally of said shoe bottom assembly, and means herein illustrated as a forepart shaping member having the shape of the forepart of a last constructed and arranged to move longitudinally of the shoe bottom assembly to operate on an upper secured thereto. In the illustrated organization said heel block is rigidly mounted in a fixed position and an actuator in the form of a treadle is provided for moving the forepart shaping member toewardsly to impart the desired shape to the upper.

These and other features of the invention will now be described with reference to the accompanying drawings and pointed out in the appended claims.

In the drawings,

Fig. 1 is a right side elevation illustrating a machine embodying the features of the present invention; and

Fig. 2 is a section taken on the line II—II of Fig. 1.

Referring to Fig. 1, a standard 10 of generally triangular shape is secured to the top of a bench 12 by screws or bolts 14 extending through outwardly flanged portions 16 and 18 of the base of the standard. The front of the illustrated ma-

2

chine is identified by the inclined face 11 of the standard. The rear portion of the standard has a vertical plane surface extending widthwise of the standard to which an upwardly extending plate 20 is secured by screws 22. Secured to the upper end portion of said plate by screws 24 is a work supporting member 26 herein illustrated as a wooden block having the general shape of the heel portion of a last.

- 10 For clamping the heel portion of a shoe bottom against the upper surface of the work support 26 a cylindrical roll 28 is eccentrically mounted on a cross shaft 30 journaled in suitable bearings in the upper portions of parallel vertical plates 32 (Fig. 2) secured by bolts 34 to opposite side portions of the standard 10. For actuating the roll 28 to clamp a shoe bottom against the work support 26 a hand lever 36 is fixed in said roll and arranged to project radially therefrom.
- 20 For shaping the forepart of a prefitted upper secured to a shoe bottom a form 38 herein illustrated as a wood block having the general shape of the forepart of a last is secured by screws 40 to the upper portion of a rigid plate 42 secured to a plane surface in the forward portion of a mounting member 44 similar in construction to the standard 10 and pivotally mounted on a cross shaft 46 extending through a rearwardly projecting portion 48 (Fig. 2) of the standard 10 and 30 through lugs 49 in the member 44. The forepart shaping form 38 is normally held in its retracted position illustrated in Fig. 1 with the upper portion of the plate 42 in contact with the plate 20 by a tension spring 50 the rear end of which 35 engages a pin 52 in the mounting member 44 and the forward end of which engages a like pin 54 in the standard 10. For swinging the mounting member 44 in a clockwise direction, as seen in Fig. 1, to actuate the forepart shaping form 40 38 a treadle 56 is connected by a link 58 to a lug 60 projecting rearwardly from the mounting member 44.

In the operation of the illustrated machine a shoe having an open back part is arranged in 45 inverted position and advanced heel foremost to bring the upper 62 into engagement with the form 38 as shown in Fig. 1. By the same heelward motion the shoe bottom, which, as herein illustrated, comprises a sole 64 and a heel 66, is advanced into its position illustrated in Fig. 1. In this position the rear or heel portion of the shoe bottom is positioned between the work support 26 and the roll 28, the roll being so arranged as to permit the heel portion of the shoe bottom to pass freely between the roll and the

work support. The hand lever 36 is now swung in a counterclockwise direction, as seen in Fig. 1, to cause the roll 28 to exert a clamping action upon the heel 66 thereby gripping the bottom unit securely against the work support 26. The operator now depresses the treadle 56 to advance the form 38 into the upper 62, thereby stretching and expanding it to its final shape. After holding the form so advanced for a brief interval the treadle is permitted to return to its rest position. The roll 28 is then turned in a clockwise direction to disengage it from the heel 66 whereupon the shoe is moved toewardly from the machine.

Having thus described my invention, what I claim as new and desire to secure by Letters Patent of the United States is:

1. A shoe machine comprising a support for an end portion of a shoe bottom constructed and arranged to engage the foot facing surface of said shoe bottom, an eccentrically mounted presser member for clamping said shoe bottom against said support, means for positively holding said presser member against bodily movement longitudinally of said shoe bottom, and means constructed and arranged to move longitudinally of the shoe bottom to operate on an upper secured thereto.

2. An upper shaping machine comprising means for mounting an end portion of a shoe bottom, an eccentrically mounted clamp for gripping the shoe bottom against said mounting means, a hand lever for operating said clamp, means for positively holding both the mounting means and the clamp against movement longitudinally of said shoe bottom, and means constructed and arranged to move longitudinally of the shoe bottom within an upper secured thereto, thereby to shape said upper.

5 3. An upper shaping machine comprising a block having the shape of the heel end portion of a last, means rigidly mounting said block in a fixed position for supporting the heel end portion of a shoe bottom, an eccentrically mounted role for clamping the shoe bottom against the block, means for positively holding said roll against bodily movement longitudinally of said shoe bottom, a forepart shaping member having the shape of the forepart of a last, means for mounting said forepart shaping member, and an actuator constructed and arranged to act on said mounting means to force said forepart engaging member into an upper secured to said shoe bottom.

KARL ENGEL.
